CLAIM

The ornamental design for a vehicle tire tread, as shown and described.

DESCRIPTION

FIG. 1 is a front perspective view of our new vehicle tire tread design, it being understood that the depicted tread pattern extends over the entire circumference of the tire, FIG. 1 also indicating a detailed view area; FIG. 2 is front elevation view thereof; FIG. 3 is a rear elevation view thereof; FIG. 4 is a right side view thereof; FIG. 5 is a left side view thereof; FIG. 6 is a top view thereof; FIG. 7 is a bottom view thereof; FIG. 8 is a rear perspective view thereof; FIG. 9 is a detailed front perspective view of FIG. 1; FIG. 10 is a detailed front elevation view of FIG. 2; and, FIG. 11 is a detailed rear perspective view of FIG. 8. In the drawing figures, the tire features shown in broken lines indicate environmental subject matter only, and form no part of the claimed design.
